UNITED STATES PATENT OFFICE.

JAMES BARDSLEY, OF OLDHAM, COUNTY OF LANCASTER, ENGLAND.

GAS-REGULATOR.

SPECIFICATION forming part of Letters Patent No. 398,021, dated February 19, 1889.

Application filed June 25, 1888. Serial No. 278,089. (No model.) Patented in England May 6, 1886, No. 6,134.

To all whom it may concern:

Be it known that I, JAMES BARDSLEY, a subject of the Queen of Great Britain and Ireland, of the firm of Hargreaves & Bardsley, 5 brass founders and finishers, of the Union Brass Works, Oldham, county of Lancaster, England, have invented an Improvement in Gas-Regulators, (for which I, in conjunction with one Riley Hargreaves, obtained a patent in Great Britain, No. 6,134, dated May 6, 1886,) of which the following is a specification.

My invention relates to the apparatus employed to promote uniformity of gas-pressure by reducing excessive pressure down to a fixed 15 regulated maximum of pressure, as is well understood. In well-known forms of such apparatus bells or flanged disks are used, and it is to such regulators that my invention relates. In such regulators the rim of the bell 20 dips into an annular trough partly filled with mercury, and the greater or less immersion of the said rim in the mercury causes a variation in the pressure, so that it is not possible to obtain a very delicate regulation. To 25 obviate this defect a tumbling loaded lever has been used; but I do not find this to act perfectly. I employ for the purpose a lever which is mounted upon a fulcrum and is provided with an adjustable tubular arm which 30 is loaded with fluid. This lever bears upon the bell or float of the regulator. When the bell rises, the fluid moves in the lever, so as to shift the center of gravity nearer to the vertical line which passes through the fulcrum, thereby reducing the load upon the bell, 35 a contrary effect being produced when the bell sinks. I construct the apparatus so that the valve-spindle can be withdrawn and replaced without disconnecting the regulator 40 from the gas-pipes.

My invention will be clearly understood when described with reference to the accompanying drawing.

The said drawing represents a vertical section taken through the center of the improved regulator.

In the drawing, *a* is the compensating-lever, *b* is the bell or float. *c* is the valve-spindle, and *d d'* are the regulating-valves.

50 The gas is admitted at *e* and flows through the annular spaces between the valves and

the valve-seatings *f f'* to the outlet at *g*. After the gas has passed the valves it has access to the inside of the bell *b*, which floats in mercury which is contained in the annular 55 trough *h*, the bell being more or less raised, according to the pressure of the gas, and as a consequence the passages in *f f'* are more or less restricted.

The action of the regulator as so far described is not new. It will be seen that as the mercury has a greater specific gravity than the bell the latter will have a greater buoyancy when in a low position than when in a higher position, and therefore that a slightly 60 greater pressure is required inside the float to sustain it in a higher position as compared with a lower. The result is that a higher pressure of gas when entering at *e*, or a reduced outflow at *g*, entails a higher pressure when leaving at *g*, although the office of the apparatus is to reduce the issuing gas to a constant pressure. The compensating-lever *a* is intended to reduce the variations in the pressure of the issuing gas as well as to determine the said 65 pressure. The said lever consists of a bell-crank lever, *a a'*, which is loaded by means of the tube *a'*, which contains mercury. This tube has an exterior screw-thread, whereby it is adjustably secured in a tapped hole in the 70 vertical arm *a* of the lever. The horizontal arm *a'* of the lever is provided with a small wheel, *a''*, which rests upon the nut *b'*, whereby the bell *b* is secured to the valve-spindle *c*. When the bell rises, owing to an increased 75 pressure or decreased outflow of gas, the lever is tilted upon its fulcrum at *i*, whereby the mercury in the tube *a'* is caused to flow toward the fulcrum, thereby reducing the downward pressure upon the bell and compensating for the reduced displacement of mercury in the trough *h*. On the contrary, when the bell sinks the mercury flows in a direction away from the fulcrum, and thus increases the load upon the bell and compensates for 80 the increased submergence. It will be seen that the wheel *a''* always bears downward upon the bell. The amount of this downward pressure, together with the floating weight of the bell and the dead weight of the spindle *c* and 85 valves *d d'*, determine the pressure of the issuing gas. The pressure can be reduced by 90 95 100

turning the tube in the unscrewing direction, which will move it in the direction indicated by the arrow, so that the left-hand end of the tube does not project so far from the fulcrum, 5 and, on the contrary, by screwing the tube farther in, so as to move the tube in a contrary direction to the indication, the downward pressure upon the bell is increased. When adjusted, the tube is secured by means 10 of a set-screw, a^4 . The screw indicated by the dotted lines at j is introduced when the apparatus is being prepared for transit, the said screw bearing against the end of the tube a' and through the lever a a^2 , forcing the bell 15 downward, so that a valve, k , closes the opening in l , and thereby prevents the mercury in h from passing down into the gas-passages. The valve d' is secured to the spindle by means 20 of a pin. When the nut b' is unscrewed and the two screw-plugs m n are removed, the valve drops down through the opening at m , and the pin can then be removed and the valve taken 25 off the spindle. Access can then be had to the seating f' , which is unscrewed and removed, the valve-spindle then coming out of

its place. By a converse of these operations the parts are got into their positions.

What I claim as my invention is—

1. As a means for adjusting the load upon the bell of a gas-regulator, the lever a , having 30 in the horizontal arm a^2 a wheel, a^3 , resting upon the bell b , and a tubular chamber, a' , screwed into the vertical arm a and charged with mercury or fluid, the said part a' being adjustable in the arm by turning the said part 35 in the direction for screwing or unscrewing, substantially as set forth.

2. In a gas-regulator, the lever a a^2 , mounted upon a fulcrum, i , provided with a wheel, a^3 , and with an adjustable tube, a' , containing 40 mercury, in combination with the bell b , the spindle c , the valves d d' , and the valve-seatings f f' , substantially as set forth.

In testimony whereof I have signed my name to this specification in the presence of two sub- 45 scribing witnesses.

JAMES BARDSLEY.
